HAIR DRESSING COMB

Arthur H. Madore, Los Angeles, Calif.

Application April 28, 1937, Serial No. 139,569

3 Claims. (Cl. 132—19)

My invention relates generally to combs, and more particularly to a comb that may be conveniently and effectively utilized in the formation of curls in the hair, and also for applying liquid solutions to the hair for the purpose of tinting and dyeing the same.

The principal object of my invention is to provide a comb of the character referred to, having a main body portion provided with conventional comb teeth, and a handle extending from one end of said toothed body, which handle comprises a pair of spaced parallel fingers that receive between them the end of a strand or lock of hair that is wound onto the handle and formed into a curl as said comb and handle are rotated.

A further object of my invention is to provide a hair-dressing comb wherein the handle portion is divided to form a pair of spaced parallel fingers, and to mount on said handle a detachable member carrying a single finger that lies parallel and cooperates with the spaced parallel fingers of the comb handle in the formation of curls and in the dressing of hair.

A further object of my invention is to provide a comb having detachable parts that may be conveniently used for applying liquid solutions to the hair for the purpose of tinting or dyeing the same.

With the foregoing and other objects in view my invention consists in certain novel features of construction and arrangements of parts that will be hereinafter more fully described and claimed and illustrated in the accompanying drawing, in which:

Figure 1 is a side elevational view of a comb constructed in accordance with my invention.

Fig. 2 is a cross section taken on the line 2—2 of Fig. 1.

Fig. 3 is a side elevational view partly in section and showing a modified form of the hair dressing comb.

Fig. 4 is a cross section on the line 4—4 of Fig. 3.

Fig. 5 is an elevational view of the handle portion of my improved comb and showing an attachment which, when used, provides three parallel fingers for use in curling the hair.

Fig. 6 is a cross section taken on the line 6—6 of Fig. 5.

Fig. 7 is a cross section taken on the line 7—7 of Fig. 5.

Fig. 8 is a plan view of the form of comb illustrated in Fig. 5.

Fig. 9 is an elevational view of a portion of the toothed body of the comb and showing an attach-

ment that is utilized in forming a swab for applying tinting solution to the hair.

Fig. 10 is a cross section taken on the line 10—10 of Fig. 9.

Fig. 11 is a side elevational view of a portion of the comb body and showing an attachment utilized for applying liquid dye to the hair.

Fig. 12 is a cross section taken on the line of Fig. 11.

Referring by numerals to the accompanying drawing, and particularly to the construction illustrated in Figs. 1 and 2, 10 designates a comb body which may be formed of hard rubber, Celluloid, light-weight metal, or the like, and which includes the conventional back and a series of 15 comb teeth 11.

Projecting from one end of this comb body is an integral member 12 that functions as a handle while the comb is being used to pass the teeth through the hair, and this member is provided 20 with a centrally arranged longitudinally disposed slot 13, and the portions to the sides of this slot constitute fingers 14, having tapered ends 15, and these fingers are utilized in hair-curling operations.

These fingers 14 are practically semi-oval in cross section, as illustrated in Fig. 2, and the inner faces 16 of said fingers, or the faces that are formed by the slot 13, are flat and parallel.

In the use of this comb in curling hair, the end 30 of a strand or lock of hair is placed in the slot 13 and clamped to one or both of the fingers by the thumb and fingers of the operator's hand, and with the other hand the comb is now rotated so as to wind the hair around the fingers 14.

After the winding operation has been completed, the curled hair is engaged by suitable means, preferably a hair-pin, to hold the curl in shape, and the fingers 14 are now withdrawn from the curl.

In the modified construction illustrated in Figs. 3 and 4, the body of the comb is provided at one end with a short extension 17, upon which is removably positioned a socket 18, preferably formed of sheet metal. One end of this socket projects beyond member 17, and suitably secured in this projecting portion are the inner ends of a pair of spaced parallel fingers 19, the outer ends 20 of which are tapered.

In this construction the socket 18, carrying the 50 fingers 19, may be interchangeably used with different comb bodies, and in the curling of hair the operation of this form of comb and the spaced fingers is identical with that form of comb illustrated in Figs. 1 and 2.

5 In the modified construction illustrated in Figs. 5 to 8 inclusive, the open flat loop 21 of sheet-metal is adapted to be removably positioned on that portion of the extension 12 adjacent the comb body 10, and carried by said loop is a finger 22 which, when the loop is properly applied to the extension 12, occupies a position parallel with and spaced apart from the fingers 14.

10 Thus when the loop is applied to the comb, finger 22 occupies a position directly opposite the slot between the fingers 14, and thus three spaced parallel fingers are provided for engaging and curling the hair.

15 In the modified construction illustrated in Figs. 9 and 10, and inverted U-shaped clip 23, of resilient metal, is adapted to be positioned on the back of the comb body 10 near the outer end thereof, and carried by this clip is a finger 24 that occupies a position parallel with and spaced apart from the back of the comb.

20 When this construction is utilized for applying tinting compounds to the hair, a body of fibrous material, for instance absorbent cotton, is wound on the finger 24 to form a swab, and the same is saturated with the tinting compound and then applied to the hair.

25 In the modified construction illustrated in Figs. 11 and 12, an inverted U-shaped clip 25, formed of resilient metal, is adapted to be removably positioned on the back of the comb body 10 adjacent the outer end thereof, and formed integral with the end portions of this clip are pairs of up-standing ears 26 that are adapted to receive and grip the back 27 on the small brush.

30 This particular construction is utilized for applying dye to the hair, and when such practice is carried out the bristles of the brush are dipped in the dye and then applied to the hair.

Thus it will be seen that I have provided a hair dressing and curling comb that is relatively simple in construction, inexpensive of manufacture, and very effective in performing the functions for which it is intended.

5 It will be understood that minor changes in the size, form and construction of the various parts of my improved hair dressing comb may be made and substituted for those herein shown and described without departing from the spirit of the 10 invention, the scope of which is set forth in the appended claims.

15 I claim as my invention:

1. A hair dressing and curling comb comprising a toothed comb body, a pair of substantially 15 parallel spaced fingers projecting from one end of said comb body and constituting a handle therefor, and a third finger detachably mounted on the comb body and occupying a position spaced apart from and parallel with said pair of 20 fingers so as to cooperate therewith in hair curling operations.

2. A hair dressing comb comprising a toothed comb body, a projection at one end thereof, a clip detachably mounted on said projection and a 25 hair curling finger projecting from said clip.

3. A hair dressing comb comprising a toothed comb body, a handle projecting from one end thereof, which handle is divided lengthwise to form a pair of substantially parallel fingers, a 30 clip detachably mounted on said handle and a hair curling finger projecting from said clip and occupying a position substantially parallel with the divided portion of said handle.

35 ARTHUR H. MADORE.
